UNITED STATES PATENT OFFICE.

JAMES I. MILLER, OF BLACKSVILLE, WEST VIRGINIA.

JACK HANGER.

Application filed March 15, 1924. Serial No. 699,477.

To all whom it may concern:

Be it known that I, JAMES I. MILLER, a citizen of the United States, residing at Blacksville, in the county of Monongalia and 5 State of West Virginia, have invented new and useful Improvements in Jack Hangers, of which the following is a specification.

This invention relates to attaching devices, and more particularly to what I term a jack 10 hanger.

One of the main objects of the invention is to provide a device of simple construction and operation which may be readily applied to a jack for use in connection with automobiles, and may be readily produced at 15 small cost. A further object is to provide a device of this character which, when applied, will facilitate application of the jack and will insure proper positioning thereof 20 relative to the automobile axle. Further objects will appear from the detail description.

In the drawings:

Fig. 1 is a side view of the device as applied;

25 Fig. 2 is a bottom view of the device;

Fig. 3 is a side view of the device as applied to a ratchet type of jack.

The device includes a clamp 1 which is formed of two plates 2 and 3 which are forced toward each other by means of bolts 4 passing through the ends of the plates and nuts 5 threaded onto these bolts. Plate 3 is provided, at one end, with a rectangularly disposed arm 6 to which is riveted one 30 end of a spring clamp 7 of approximately three-quarter circular shape, the free end portion 7^a of this clamp or spring being bent outwardly and turned over to provide a transverse sleeve 7^b. Member 7, which forms 35 a clamping bow, is formed from a single piece of spring steel or other suitable resilient material. The clamping plates 2 and 3 are provided with central arcuate portions 2^a and 3^a, respectively, which are adapted 40 to fit about the neck portion of head *j* of a screw jack *J* of a known type adapted for use in connection with automobiles, thus providing simple and efficient means for securing the device to the jack without necessitating any changes in construction thereof. When the device is applied it is positioned so that plates 2 and 3 and bow mem-

ber 7 are disposed in parallelism with head *j* of the jack, the bow member extending above and over the jack head. 55

When it is desired to use the jack it may be readily and accurately positioned by passing bow member 7 over and about axle *a* of the automobile, after which the jack is released so as to turn about the axle with head *j* positioned beneath and in contact with the axle, the jack being then extended so as to rest upon the supporting surface, after which the jack is operated so as to raise the axle *a*. This provides very simple means by which 60 the jack may be quickly applied to the axle and is so held as to insure proper aligning of the jack with the axle during raising thereof. In addition, this provides very 65 simple means whereby the jack can be 70 quickly and easily applied without loss of time in positioning the jack to insure proper aligning thereof with the axle. In Fig. 3 I have illustrated the device as applied to a 75 jack *J'* of the ratchet type. The device, when applied to a ratchet type of jack, is used in the same manner as with a screw jack. This device can be readily produced at small cost and can be quickly applied to either a screw jack or a ratchet jack of standard construction, thus providing a device which is 80 very efficient and can be readily produced and applied at small cost.

What I claim is:

1. In a device of the character described, 85 a clamp, and a resilient bow member secured at one end to the clamp and free at its other end, said member extending above the clamp.

2. In a device of the character described, 90 a clamp, and a bow shaped flat spring secured at one end to the clamp and extending above the same, the other end of the spring being free and disposed to facilitate placing of the same about an article to be operated upon. 95

3. In a device of the character described, 100 two opposed plates, means for forcing said plates toward each other, one of the plates being provided at one end with a rectangularly disposed arm, and a flat spring of bow shape secured at one end to said arm and extending above the plates, the other end of the spring being free.

4. In a device of the character described,

two opposed plates, means for forcing said plates toward each other, each of the plates being provided with an outwardly curved arcuate portion, and a flat spring secured at 5 one end to one of the plates and extending above the same, the other end of the spring being free.

5. In combination with a jack, a resilient bow shaped member secured at one end to 10 the jack and extending above the head of said

jack, the other end of said member being free.

6. In combination with a jack, a flat spring secured at one end to the head of the jack, said spring being of bow shape and extending over the jack head, the other end of the spring being free. 10

In testimony whereof I affix my signature.

JAMES I. MILLER.
